UNITED STATES PATENT OFFICE.

ARTHUR J. HOWARD, OF MALDEN, MASSACHUSETTS, ASSIGNOR TO THE
WIRE GRIP FASTENING COMPANY, OF CHICAGO, ILLINOIS.

DESIGN FOR A NAIL OR SLUG.

SPECIFICATION forming part of Design No. 24,758, dated October 15, 1895.

Application filed September 9, 1895. Serial No. 562,008. Term of patent 14 years.

To all whom it may concern:

Be it known that I, ARTHUR J. HOWARD, of Malden, in the county of Middlesex and State of Massachusetts, have invented and produced 5 a certain new and useful Design for a Nail or Slug, of which the following is a specification, reference being had to the accompanying drawings, forming a part thereof.

Figure 1 of the drawings is an isometric 10 view of a nail or slug, showing my design; and Fig. 2 is an end view thereof.

My design relates to nails or slugs for ornamenting boot or shoe heels.

The leading feature of my design consists 15 in a central web, lozenge-shaped in cross-section with thicker substantially-cylindrical portions at the two opposite longitudinal edges of the web.

The nail or slug d is composed of a central web d' , lozenge-shaped in cross-section, and 20 the substantially-cylindrical portions d^2 of the nail or slug are located at the two opposite longitudinal edges of the web.

I claim—

The design for a nail or slug, substantially 25 as set forth.

In testimony whereof I have signed my name to this specification in the presence of two subscribing witnesses.

ARTHUR J. HOWARD.
